Corporation, Long Island City, N. Y., a cor-
poration of New York

Application November 7, 1933, Serial No. 696,958

18 Claims. (Cl. 20—18)

This invention relates to revolving doors, and more particularly to doors of the type in which the several leaves are normally retained in fixed radial positions with reference to one another, 5 but in which the leaves may be collapsed or folded into book form when desired.

It is an object of the invention to provide on the leaves and on the central support therefor cooperating means adapted to hold the leaves 10 in place, to produce a controlled planetary movement of the inner portions of the leaves about the central column when the leaves are folded, and to provide extensive inter-engaging surfaces effective in all positions of a leaf to positively 15 assure parallelism between the leaf and the axis of the central column. To this end provision is desirably made upon the central support of a non-circular central gear-like member which participates in the control of the planetary 20 movements of all the leaves and which has a guiding and retaining flange surrounding but spaced from the gear portion with surfaces of appropriate contour for cooperating in the control of the movements of the leaves, and upon 25 each leaf a block or gear member of appropriate shape for cooperating at all times with both the central gear and with the surrounding guide flange.

It is a further and important object of the 30 invention to provide novel and improved detent means for normally retaining each leaf in radial positions, such detent means comprising alternatively effective spring toggle members, the arrangement being such that one or the other 35 must be forced to and beyond dead center in order to move the door leaf away from its normal position.

With this arrangement a detent structure 40 is provided which is adapted to be accurately and permanently set to yield in response to a predetermined pressure since no variable factor such as friction, which develops in prior structures to cause a departure from the initial and intended resistance, can have any substantial 45 effect in altering the resistance of the toggle mechanism of the present structure which such mechanism is designed to interpose.

A further feature of the toggle mechanism 50 resides in the fact that the initial resistance to movement from normal position is not so great as that which occurs at and just before the point where the dead center position of the toggle is reached. As a consequence the door leaves may be securely safeguarded against un- 55 intended collapse but may nevertheless provide

a limited yielding effect. This effect is highly desirable for the protection of persons who may unobservantly walk or stumble against one of the leaves and of persons who may be overtaken and struck from behind by a leaf when 60 passing through the door way.

The toggle mechanism is well adapted for employment with the leaf supporting and controlling means embodied in the illustrative form of the invention disclosed herein. This mechanism, however, is not confined to use with any particular leaf movement nor is its application confined to any particular form of spring loading means.

A further object of the invention is to provide 70 spring detent means adapted to yield under a predetermined load, and means for selectively determining and setting such predetermined load without the necessity of compressing the spring of said detent. To this end it is a feature of the preferred embodiment of the invention as illustrated herein that the detent mechanism and the loading spring are connected 75 through force multiplying means, and that provision is made for altering the multiplication 80 ratio while maintaining the stress of the spring unchanged.

The importance of assuring that the detent mechanism will always yield in response to a predetermined force lies in the fact that different states have different regulations and statutes 85 which specify a maximum force under which the leaves must yield under panic conditions.

For ordinary folding of the leaves into book form to clear the door opening for the reception 90 and delivery of merchandise, it is frequently desirable for the operator not to be compelled to exert this "panic" force. With the spring loading means of the present invention the spring loading of the detent may be reduced at will to 95 any desired point and reestablished at the predetermined maximum after the leaves have been returned to normal without the necessity of relieving and restressing the spring and hence without the necessity of overcoming the spring 100 resistance.

Other objects and advantages will hereinafter appear.

In the drawings forming part of this specification:

Figure 1 is a view in sectional elevation of a door structure embodying features of the invention;

Figure 2 is a horizontal, sectional view illustrating the structure of Figure 1;

Figure 3 is a fragmentary, plan view of the inner end of one of the door leaves;

Figure 4 is a fragmentary, horizontal sectional view through one of the control devices, the leaves being illustrated in collapsed condition;

Figure 5 is a fragmentary, detail view in vertical section illustrating a feature of the door leaf construction whereby the space around the detents is sealed against the admission of drafts;

Figure 6 is a fragmentary, detail perspective view illustrating a pair of detents and their associated plunger in disassembled relation;

Figure 7 is a fragmentary sectional plan view through the central supporting mechanism and one of the door leaves, the normal positions of the other leaves being indicated in dash lines and one collapsed condition of all the leaves being indicated in dot and dash lines;

Figure 8 is a detail sectional view taken on the line 8-8 of Figure 7 looking in the direction of the arrows; and

Figure 9 is a fragmentary view in sectional elevation of the mechanism illustrated in full lines in Figure 7.

The door is shown mounted in an opening in a building structure of usual form, the opening being bounded by a floor 1, a ceiling wall 2 and arcuate side walls 3. The door leaves 4 are supported from a central, vertical shaft 5 which extends up through a slot in the ceiling wall 2 and which is revolvably suspended from carriage 6. The carriage is in turn mounted upon a track (not shown) and may be slid along the track to locate the folded leaves at one side of the opening in the position indicated at 7 in Figure 2.

Upon the central shaft 5 provision is made of upper and lower discs 8 which are fixedly secured to the shaft for supporting the leaves 4 and controlling the movements of the leaves relative to the shaft. Each disc includes a raised inner flange 9, a raised outer flange 10 and four raised bosses or pins 11, preferably of the same height as the flanges. The inner flange is so contoured that with the bosses 11 it constitutes a gear of non-circular form upon which the leaves are adapted to have planetary movement with reference to the shaft 5.

Each leaf has mounted in it upper and lower housings each composed of complementary plates 12 and 13 (Fig. 9). Ears 14 and 15 at the outer ends of the plates are clamped together by a bolt 16 and a nut 17. The plates have side flanges 17a which stand in abutting relation, and they may be exteriorly supported by other portions of the leaves to hold them securely together. At the inner end of the plate 13, shown in Figure 9, provision is made of a block or pinion member 18 which is fixed to the plate as by screws 19, and which moves in the annular space between the inner and outer flanges of the disc 8.

Each block 18 and each disc 8 include inter-engaging surfaces arranged to have extensive sliding contact with one another at the inner and outer sides of the block and to firmly support and control the block throughout a swinging movement in the course of which the block is turned through substantially 135 degrees and moved bodily in a planetary path through a lesser angle.

Each block 18 is provided with a circular lobe 20 which normally bears in a complementary bearing recess 21 formed in the outer face of the flange 9. At the opposite end of the block

from the lobe 20 provision is made of a broad arcuate bearing surface 22 concentric with the bearing surface of the lobe 20. The surface 22 bears against an inner arcuate surface 23 of the flange 10, which surface is concentric with the bearing surface of the recess 21. When the door leaf is swung away from normal position it is guided first by the arcs 20 and 22, 21 and 23 until such movement is arrested by engagement of one of the bosses 11 with the base of a notch 24 which is provided in the block 18. At this instant the surface 22 clears the surface 23, leaving the block 18 free to turn about the axis of boss 11, and at the same time an arcuate surface 25 of a tooth 26 of the block 18 will have come into full engagement with a second arcuate recess 27 of the inner flange 9. At this same time an arcuate bearing surface 28 of the block 18 which is concentric with the base of the recess or notch 24 comes into engagement with an arcuate surface 29 of the outer flange 10 which is concentric with the axis of the boss 11 and with the arcuate surface of the recess 27. The tooth 30 of the block 18 also has a portion 31 of the outer end thereof made arcuate about the same center as the base of the recess 24 and the surface 28.

In the second phase of rotation of the door leaf the block is guided by inter-engagement of the boss or pin 11 with the base of the notch 24, the arcuate surface 27 with the arcuate surface 25, and the arcuate surface 29 with the arcuate surfaces 28 and 31. The second phase of rotation of the door leaf is terminated when the leaf with the block 18 affixed thereto has moved through substantially one hundred and thirty-five degrees from its original position. Throughout the entire movement the leaf is positively controlled by the extensive broad inter-engaging surfaces at the inner and outer sides of the block 18.

The right and left hand halves of the block 18 are mirror images of one another. The bosses or pins 11 are all located at the same distance from the axis of the shaft 5. The recesses 21 and 27 occur in alternation around the entire periphery of the inner flange 9, while the arcuate surfaces 23 and 29 occur in alternation around the entire inner face of the outer flange 10. As a consequence, each door leaf is capable of being swung in either direction through one hundred and thirty-five degrees from its normal radial position and to be supported and controlled in such swinging movement in the manner described.

It is desirable that provision be made of mechanism adapted to be set to interpose a predetermined yielding resistance to collapsing movement of a door leaf and that such mechanism be capable of continuously maintaining substantially the same resistance to collapse throughout the life of the structure. It is desirable, for example, that the operation and effect of the detent mechanism shall be substantially independent of regular lubrication and freedom from dust or dirt.

It is also desirable, however, that the detent mechanism, though capable of resisting collapsing movement of the leaf with a sufficient force to prevent unintended collapsing movement thereof, shall nevertheless have capacity for limited yielding movement within a narrow range against increasing resistance in the normal operation of the door. An important feature of

this invention relates to the provision of novel detent means having these desirable characteristics.

The housing formed by the plates 12 and 13 carries detent mechanism for cooperation with the periphery of the disc 8. A slide block 32 mounted in the housing carries at the forward end thereof an ear 33 through which a vertical pivot pin 34 is passed. A pair of detent arms 35 and 36 are pivotally mounted upon each pin 34, being urged apart by a compression spring 37 which is mounted between them. A clearance notch 38 (Fig. 6) is provided in the ear 33 for the outer end of the detent arm 35, and a similar notch 39 is provided in the hub portion of the detent arm 36. The shoulder at the left side of the notch 38 limits rotation of the arm 35 toward the left with relation to the slide block 32 and the shoulder at the left side of the notch 39 limits rotation of the detent arm 36 toward the right with relation to the arm 35. As a consequence, the detent arms are caused normally to occupy substantially the angular relation to one another which is illustrated in Figure 7. Each detent arm, together with the connected slide block normally constitutes a flexed toggle and these toggles are alternatively effective to resist clockwise and counterclockwise movements of the leaf by which they are carried. The slide block is spring loaded and since movement of the door in either direction from normal involves first a straightening of one or the other of the toggles with a consequent compression of the spring, any such movement is resisted with yielding but increasing force until the dead center or straightened position of the effective toggle is reached.

The slide block 32 is provided with a bore 40 at the outer end thereof for receiving one end of a compression spring 41. The spring 41 bears at its opposite end against an abutment 42 of the housing plate 12 and constantly urges the slide block 32 forward with light yielding force. The slide block is provided with an inwardly facing shoulder 43 at the lower side thereof and this shoulder cooperates with a shoulder 44 of the plate 13 for limiting inward movement of the slide block when the detents are out of action.

The slide block is also provided with a downwardly facing cam shoulder 45 for cooperating with a beveled faced lever 46. The lever 46 is supported upon a fulcrum pin 47 mounted in the housing, and rests at its outer end upon an unyielding abutment 48 of the housing plate 13. A plunger 49 mounted in a sleeve 50 is urged downward by a compression spring 51 against the outer end of the lever and holds the outer end of the lever down against the abutment 48 with substantial force. The spring 51 bears against opposed flanges on the head of the plunger 49 and on the base of the sleeve 50. The sleeve 50 is fixed on a rack bar 52 which is slidably mounted in the housing. A pinion 53 meshes with the rack bar 52. The shaft of the pinion 53 is provided with a square opening 54 into which a key may be fitted to rotate the pinion for sliding the plunger in and out along the lever 46. The spring may be set at any desired position along the lever to cause the initial collapsing movement of the door leaf to be resisted by any selected predetermined amount of force. The plunger may even be located directly over the axis of the fulcrum pin 47 to render the spring 51 completely ineffective.

Such position of the plunger is indicated in the dotted line showing 49a of Fig. 8. With such setting the resistance to collapse is slight since the spring 51 is the principal loading spring.

In the present construction the maximum initial resistance which can be applied is positively limited by limiting the distance which the plunger can be moved outward from the fulcrum of the lever. To this end a stop 55 is provided in the path of the rack bar 52, the stop being mounted upon a bolt 56 which extends upward through a slot 57 in the top housing plate 12. The bolt 56 may be moved along the slot to adjust the position of the stop 55 and may then be clamped in fixed position by tightening a nut 58 which is threaded upon the upper end of the bolt.

The detent arms 35 and 36 extend outward into slots or side openings provided in the housing 12, 13 and the inner ends normally engage respectively in notches 59 and 60 which are formed in the periphery of the disc 8. When the leaf 4, illustrated in full lines in Fig. 7, is moved clockwise toward collapsed position, the slide block 32 and the detent arm 35 jointly form a flexed toggle which must be moved to and through the straight or dead center position in order to fold the leaf. During this movement toward the straight position of the toggle, the slide block is forced back in the housing with the result that the forward end of the lever 46 is depressed by the camming action of the inclined shoulder 45 and the rear end of the lever is raised against the force of the spring 51. During this movement the spring 51 is compressed and the resistance to movement is caused to increase. Displacement short of a dead center position is automatically followed by a restoration of the displaced leaf to normal position.

When the dead center position has been crossed the slide block is returned toward its initial position and is arrested by interengagement of the shoulders 43 and 44. The detent arm 35 then rides upon the periphery of the disc 8 without interfering in any way with the free folding of the door leaf which is now entirely released. At the same time the arm 36 is limited against counterclockwise movement by engagement with a shoulder 61 of the housing 12, 13. The detent arms are caused to lie in juxtaposed relation as illustrated in Figure 4, when the leaf has been swung through either 45 degrees or 135 degrees from the normal position.

In the return movement to normal position the arm 35 first enters the notch 59 and is arrested by the notch. If the arm 36 did not thereafter engage the notch 60, however, the leaf would not be arrested in normal position, but would swing beyond such a position. It is for the purpose of assuring that the arm 36 will enter the notch 60 in this return movement that the limiting recess 39 is provided upon the hub portion of the arm 36 for preventing a greater angular separation of the arms 35 and 36.

It will be appreciated, of course, that when the leaf 4 of Figure 7 is swung in a counterclockwise direction from normal position, the detent arm 36 will operate in the same manner that the arm 35 operates when the leaf is swung in a clockwise direction from normal position. In this instance counterclockwise swinging of the arm 35 will be limited in the initial swing

ing movement of the leaf 4 by engagement with an abutment 62 of the housing 12, 13.

For the purpose of determining the collapsed positions of the leaves, each plate 12 is provided with a well 62 and each well receives a detent plunger 63 which extends through the plate 12 into engagement with the upper face of the disc 8. Above each plunger provision is made of a compression spring 64 and of a threaded plug 65 for forcing the plunger downward with yielding pressure. Each leaf has two collapsed positions 45 degrees removed from normal and two collapsed positions 135 degrees removed from normal. Four depressions are accordingly provided in the upper surface of the disc 8 for cooperating with each plunger 63, there being sixteen of these depressions in all. The depressions are all indicated by the numeral 66. An additional depression might be provided for each leaf corresponding to the radial position thereof, but since the detents determine the normal positions such depressions are unnecessary, moreover, since the plungers 63 may possibly stick, it is preferable to avoid using them where they might interfere with the collapsing movement under panic conditions.

For the purpose of preventing the admission of drafts, sleeves 67 are desirably provided around the shaft 5, above, below and between the upper and lower discs 8. Each door frame extends into substantially contiguous relation to the sleeves 67 when the leaves are in normal position, the leaves and the exterior faces of the sleeves being provided with complementary arcuate surfaces for engaging one another in normal position.

As has been mentioned, the detent arms extend into slots or openings which are provided in the sides of the housing 12, 13. For the purpose of preventing the admission of drafts around the spread inner ends of the detent arms 35, and 36, the side walls of the door are provided with flared or extended portions 68 to overlie the spread detent arms. The detent arms themselves are substantially coextensive in height with the openings in which they spread, so that the admission of drafts is effectually prevented.

The disc mounted at the top of the door is desirably arranged with the flanges extending upwardly so that a smooth exterior surface is exposed to view from below. The disc near the top of the door is inverted with respect to the upper disc so that a smooth exterior surface is presented to view from above.

The detent mechanism described is ordinarily duplicated at the upper and lower ends of the door leaves so that detents are provided for co-operation with both discs. It is feasible in some instances, however, to omit the detent mechanism at either the upper or lower end of the door and to rely upon a single set of detents in conjunction with one or the other of the discs.

While we have illustrated and described in detail certain preferred forms of our invention, it is to be understood that changes may be made therein and the invention embodied in other structures. We do not, therefore, desire to limit ourselves to the specific construction illustrated, but intend to cover our invention broadly in whatever form its principle may be utilized.

We claim:

1. In a revolving door, in combination, a central rotary support, leaves foldably mounted on

the support, and means normally retaining each leaf in radial position, comprising in each instance a notched member on the central support, a pair of normally flexed alternatively effective toggles carried by the leaf and having arms thereof engaged in the notched member, and spring means disposed to resist straightening of the toggles, the arrangement being such that one or the other of the toggles must be straightened before the leaf can be moved to collapsed position.

2. In a revolving door, in combination, a central rotary support, leaves foldably mounted on the support, and means normally retaining each leaf in radial position, comprising in each instance an abutment member on the central support, a flexed spring toggle carried by the leaf requiring to be straightened in order to free the leaf for movement to the right, and a second flexed spring toggle carried by the leaf requiring to be straightened in order to free the leaf for movement toward the left.

3. In a revolving door, in combination, a central rotary support, leaves foldably mounted on the support, and alternatively effective divergent arms carried by and associated with each leaf and each operable across the plane of the leaf and acting to resist movement of the leaf away from the normal radial position thereof in one direction with yielding but increasing force until the arm crosses the plane of the leaf and automatically ineffective thereafter to offer further resistance.

4. In a revolving door, in combination, a central rotary support, leaves foldably mounted on the support, and means normally retaining each leaf in radial position, comprising in each instance an abutment member on the central support, and a pair of angularly related rockable detent arms carried by each leaf and independently interlocking with the abutment member at opposite sides of the leaf when the leaf is in radial position, each arm being automatically tripped free of the abutment member upon folding of the leaf in a predetermined direction and to a predetermined degree.

5. In a revolving door, in combination, a central rotary support, leaves foldably mounted on the support, and means normally retaining each leaf in radial position, comprising in each instance an abutment member on the central support, a flexed spring toggle carried by the leaf and requiring to be straightened in order to free the leaf for movement to the right, and a second flexed spring toggle carried by the leaf requiring to be straightened in order to free the leaf for movement toward the left, said spring toggles comprising an element in common and a common spring acting on said element whereby the resistances to movement in opposite directions are caused to be the same.

6. In a revolving door, in combination, a central rotary support, leaves foldably mounted on the support and means normally retaining each leaf in radial position, comprising in each instance an abutment member on the central support, a flexed spring toggle carried by the leaf requiring to be straightened in order to free the leaf for movement to the right, and a second flexed spring toggle carried by the leaf requiring to be straightened in order to free the leaf for movement toward the left, spring means interposed between the retaining arms of said toggles to urge them apart, and means for limiting separation of said arms.

7. In a revolving door, in combination, a central rotary support, leaves foldably mounted on the support, and means normally retaining each leaf in radial position, comprising in each instance an abutment member on the central support, a flexed spring toggle carried by the leaf requiring to be straightened in order to free the leaf for movement to the right, and a second flexed spring toggle carried by the leaf requiring to be straightened in order to free the leaf for movement toward the left, the abutment member being a notched disc and having notches for cooperating alike with the retaining arms of all the leaves. 80
15. 8. In a revolving door, in combination, a central rotary support, leaves foldably mounted on the support, and means normally retaining each leaf in radial position, comprising in each instance a normally flexed detent device operable through a dead center condition, said device being normally so disposed with relation to the leaf and the central support that it is required to be operated to and through the dead center position in order to release the leaf for collapsing movement. 90
20. 9. In a revolving door, in combination, a rotary central support, leaves foldably mounted on the support, and means carried by each leaf for resisting movement of the leaf away from the normal radial position comprising a detent, a spring for acting on the detent to make it effective, force multiplying means interposed between the spring and the detent and forming an operating connection between them, and means for altering the mechanical advantage ratio between the spring and the detent while maintaining the stress of the spring unchanged. 95
25. 10. In a revolving door, in combination, a rotary central support, leaves foldably mounted on the support, and means carried by each leaf for resisting movement of the leaves away from the normal radial position comprising a detent, a spring for acting on the detent to make it effective, means operable to reduce the effectiveness of the spring upon the detent and to restore the initial effectiveness of the spring while maintaining the stress of the spring substantially unchanged, and means automatically limiting and terminating the restoring action when the initial effectiveness of the spring has been restored. 100
30. 11. In a revolving door, in combination, a rotary central support, leaves foldably mounted on the support, and means carried by each leaf for resisting movement of the leaves away from the normal radial position comprising a detent, a spring for acting on the detent to make it effective, means operable to reduce the effectiveness of the spring upon the detent and to restore the initial effectiveness of the spring, means automatically limiting and terminating the restoring action when the initial effectiveness of the spring has been restored, and means for adjusting the limiting means and fixing the adjustment thereof. 105
35. 12. In a revolving door, in combination, a rotary central support, leaves foldably mounted on the support, and means carried by each leaf for resisting movement of the leaf away from the normal radial position comprising a detent, a spring for acting on the detent to make it effective, a lever interposed between the spring and the detent for applying the power of the spring to the detent, and means for adjusting the spring toward and from the fulcrum of the lever. 110
40. 13. In a revolving door, in combination, a rotary central support, leaves foldably mounted on the support, and means carried by each leaf for resisting movement of the leaf away from the normal radial position comprising a detent, a spring for acting on the detent to make it effective, a lever interposed between the spring and the detent for applying the power of the spring to the detent, a fixed stop opposed to the lever for limiting movement of the lever in a direction to act on the detent, and means for adjusting the spring toward and from the fulcrum of the lever in substantial parallelism to the lever arm upon which the spring acts. 115
45. 14. In a revolving door, in combination, a rotary central support, leaves foldably mounted on the support, and means carried by each leaf for resisting movement of the leaf away from the normal radial position comprising a detent, a spring for acting on the detent to make it effective, a lever interposed between the spring and the detent for applying the power of the spring to the detent, and means for adjusting the spring toward and from the fulcrum of the lever, comprising a rack upon which the spring is mounted, said rack being movable in parallelism with the lever arm upon which the spring acts, a pinion for operating the rack, and a pinion shaft accessible from the exterior of the door leaf for operating the pinion. 120
50. 15. In a revolving door, in combination, a central support, leaves foldably mounted on the support, and means guiding the leaves in their folding movements comprising a central gear, a pinion block fixed on each leaf and movable in a planetary path about the gear, and an external guide having a series of non-concentric, arcuate guiding surfaces, said guide constantly engaging and confining the pinion block in all positions thereof and cooperating through said guiding surfaces with relatively rotating surfaces of the pinion block of substantial area, each equi-radial with the cooperative guiding surfaces, to hold the pinion block in engagement with the gear. 125
55. 16. In a revolving door, in combination, a central support, leaves foldably mounted on the support, and means guiding the leaves in their folding movements comprising a central gear, a pinion block fixed on each leaf movable in a planetary path about the gear, and an external guide having a series of non-concentric, arcuate guiding surfaces, said guide constantly engaging and confining the pinion block in all positions thereof and cooperating through said guiding surfaces with unyielding surfaces of the pinion block of substantial area, each equi-radial with the cooperative guiding surfaces, to hold the pinion block in engagement with the gear. 130
60. 17. In a revolving door, in combination, a central support, leaves foldably mounted on the support, and means guiding the leaves in their folding movements comprising a disc having an inner gear-like flange, and an outer guide flange each having a series of non-concentric, arcuate guiding surfaces, said surfaces of the flanges being paired and the surfaces of each pair being concentric with one another, and a pinion block fixed on each leaf and confined in all positions between the flanges and formed to fit successively with successive paired surfaces. 135
65. 18. In a revolving door, in combination, a central support, leaves foldably mounted on the support, each leaf having a plurality of phases of folding movement in travelling from its nor- 140
70. 75. 145
75. 150

mal position to its folded position farthest displaced from normal, and means guiding the leaves in their folding movements comprising an inner guide member and an outer guide member both on the central support, and a pinion block fixed on each leaf, said inner and outer

guide members having successive cooperating sets of concentric surfaces between which the pinion block is successively held and guided during the successive phases of folding movement.
